CLEANER FOR THE TOP COMB OF
COMBING MACHINESNorman Howard, Andover, Mass., assignor to At-
kinson, Haserick & Co., Boston, Mass., a volun-
tary association

Application August 30, 1934, Serial No. 742,087

5 Claims. (Cl. 19—116)

The object of the invention is to provide a cleaner that will successfully operate to effectively clean the top comb; one that will withstand the excessive strain to which it is subjected, and especially one that will operate with the least possible wear upon the teeth of the comb.

According to the present invention sets of cleaning blades are used operating from opposite sides of the comb. While the more common practice has been to attempt the cleaning of the comb by blades operating from but one side, attempts have, also, heretofore been made to clean the comb by a double set of blades operating from its opposite sides. In either case complete success was not achieved. While the complete success of the present invention has demonstrated that the cleaning operation can best be obtained by the use of a double set of blades, operating from the opposite sides of the comb, as the basic operating elements, as differentiated from cleaning blades operating from only one side, the use of blades operating from opposite sides of the comb are but an incident to the successful accomplishment of the cleaning operation for the successful attainment of the present invention has demonstrated that matters of tension coupled with the precise relative position of the comb with relation to the cleaning blades during successive stages of operation are of paramount importance, not only for successfully effecting the cleaning operation but, also, for the purpose of preventing injury to the blades, and especially for preventing wear upon the teeth of the comb which are more or less delicate in character.

The invention can best be seen and understood from the accompanying drawings, such portions only of the combing machine being shown as are necessary for a proper understanding of the invention.

Fig. 1 is a view of the cleaner in perspective.

Fig. 2 shows in perspective a fragmentary part of the top comb.

Figs. 3 to 6, inclusive, are sectional views of the top comb and cleaner showing the different relative positions thereof during the operation of the machine, and

Figs. 7 and 8 are plans showing the mechanism employed in giving motion to the top comb and cleaner for changing their relative positions.

Referring to the drawings 1 represents the top comb comprising a plate to which are soldered the teeth 2.

3 is the cleaner which is bracketed to the feed 4 of the comb.

Cleaner 3 comprises sets of blades 5 and 6, respectively, angularly arranged whereby the biting edges 7 and 8 thereof, respectively, will engage the opposite sides of the teeth of the comb during the combing operation. The blades of each set are each substantially square or rectangular in form and are made of relatively thin but highly tempered steel. The blades are borne by a rectangular frame 9 to which the top edge portions of the blades are securely bound by strips 10 secured by screws 11 passed through the strips on the inside, thence through slots 12 in the blades and fastening into the side bars 13 of the frame. Secured to the frame are brackets 14 having extension to connect with the feed 4 and provided with turned ends 15 bound to the under part 41 of the feed by means of bolt connections 16.

The blades 5 are backed by sectional plates 16 bound to the frame by the same fastenings as secure the blades 5. The sectional plates 16 act to reinforce and stiffen the blades 5 and prevent their easy bending.

The blades 6 are bent blades, each of the blades being provided with a lateral bend 17 forming a rib and by means of which the fore edge portion 18 of the blade, or that portion thereof lying between the bend 17 and the biting edge of the blade, is turned inwardly out of the plane of its rear edge portion 19 or that portion thereof lying between the bend 17 and the inner edge of the blade bound to the frame as aforesaid. The bend 17 in the blade, acting to reinforce or strengthen it, lies well back of the biting edge 8 of the blade, preferably a little forward of the centre of the blade, but not so far back but that the fore edge portion of the blade, in an amount extending well back of its biting edge, will be substantially inflexible to bending upon an application of force to the biting edge tending to outwardly flex the blade by displacing this edge, the flexing of the blade, when occasioned by the application of a displacing force to the biting edge of the blade, being confined to that portion 19 of the blade lying between the bend 17 in it and the bound inner edge portion of the blade. Consequently the blade will flex only to a relatively high degree of force, and, when the blade is tensioned by such flexing, the biting edge of the blade will exert a very high degree of resistance to any force tending to displace it. In other words, the blade 6 is so reinforced or stiffened that

that portion of the blade lying adjacent to but well back from its biting edge will not flex or bend upon an application of force to the biting edge tending to outwardly flex or bend the 5 blade, for if this portion of the blade is allowed to flex or bend, at least with any degree of freedom, the blade will be substantially inoperative.

The respective sets of blades are secured to the frame in such manner that in their normal 10 arrangement the biting edge 8 of the blades 6 will preferably engage the inner face of the blades 5 at a point inwardly removed from the biting edge 7 of the blades 5. In other words, the blades 5 have extension beyond the biting edge 8 of the 15 blades 6. Preferably this extension is about one-eighth of an inch.

Reference will now be made to the relative movements of the feed (which carries the cleaning blades and which accordingly have the same 20 motion as the feed) and that of the top comb in the normal operation of the combing machine. In the normal operation of the machine with the feed at the limit of its back and down movement, the top comb will then be at the limit of its highest raised position. The feed then begins to raise and the top comb to come down. As the feed raises to the limit of its upward movement the top comb will have come down to the limit of its 25 downward movement. The feed will now begin to come forward. The top comb will also move forward, their relative positions not appreciably changing. As the feed reaches the limit of its forward movement the top comb will have come forward to the limit of its forward movement and 30 has not raised. After completing its forward movement the feed begins to lower and go back while the top comb begins to raise. The feed then completes its down and back movement, the comb at the same time moving up and back. These 35 movements, together with the difference in the relative movements of the feed, to which the cleaning plates are secured, and the top comb, are availed of for assisting in the cleaning operation, and are obtained as follows in the operation of the 40 machine (see Figs. 7 and 8):

The top comb is borne by an arm 20. The feed rests upon the cushion plate 21 (forming a part 45 of the nipper not shown). Connecting with the under part or section 4¹ of the feed to which 50 part the cleaner is secured, as aforesaid, is an arm 22. Both the arms 20 and 22 are pivotally secured at points 23 and 24, respectively, to the arm 25 of a lever 26 pivoted at the point 27. In this connection it will be observed that the arm 20, bearing the top comb, is pivotally secured to the arm 25 at a point farther removed from the 55 pivotal point or fulcrum of the lever 26 than is the arm 22. This together with the angular form of the arm 22 will enable a differential movement to be imparted to the arms 20 and 22 as the lever is turned, both arms being moved simultaneously in the same direction but with a difference in their extent of movement, the arm 20 being moved farther than the arm 22. In operative engagement with the opposing arm 28 of the lever 26 is the arm 29 of a lever 30 pivoted at 31. The arm 29 has sliding engagement in its connection with the arm 28, the arm 29 being 60 provided with a slide 32 which operates within a way 33 on the arm 28. The opposing arm 35 of the lever 30 bears a cam bowl 36 engaging a cam 37 on a shaft 38. The cam bowl 36 is held in normal engagement with the peripheral edge of 65 the cam 37 by means of a spring 39 connecting

with the arm 35 through a connecting link 40. As the cam 37 is rotated in the operation of the machine both the feed, with attached cleaner, and the top comb will be moved alternately forward and back with relative change in their extent of movement, respectively, and with dwell at 70 the limits of forward and reverse movement.

The top comb is moved vertically with alternate up and down movements in the following manner: Arranged beneath the arm 20 bearing the top comb is the extended arm 45 of a lever 46 pivoted at the point 47. The arm 20 has slidable engagement with the arm 45 by means of a roller 48 on the arm 20, the roller being held in normal contact with the arm 45 by means of a spring 49 connected to the arm 20. The opposing arm 50 of the lever 46 bears upon its end a cam bowl 51 which has engagement with the peripheral edge of a cam 52 fixed to the shaft 38. With the parts thus arranged the top comb, borne by the arm 20, will be moved vertically alternately upward and downward as the cam 52 is turned with dwell at the limits of the up and down movement.

The feed, and especially the bottom part or section 4¹ thereof, to which the cleaner 3 is secured is moved alternately up and down as follows: As previously described the feed rests upon the cushion plate 21 of the nipper mechanism. This plate is borne by the arm 54 of a lever 55 pivoted at the point 56. The opposing operating arm 57 of this lever pivotally connects with a link connection 58 pivoted at the point 59 to a lever 60 fulcrumed on the shaft 61 and bearing a cam bowl 62 which engages the peripheral edge of a cam 63 on the shaft 38. As the cam 63 is turned the cushion plate 21 and with it the feed and cleaner will be moved vertically up and down with dwell at the extremes of movement, and especially when the cushion plate is in its extreme down position.

The form and arrangements of the various cams and connecting parts just described operate simultaneously during the operation of the machine in such proper timed relationship as will impart to the top comb and cleaner the movements previously referred to. In this connection it will be understood that the illustrations of these mechanisms and description thereof is diagrammatic, forming as they do in themselves no part of the present invention although incidental to its accomplishment. In the machine the various parts constituting these mechanisms are provided with other features, not shown, especially those permitting of their adjustment as is necessary in a machine of this kind, all of which is well known to those skilled in the art.

The normal arrangement of the cleaning blades and the top comb is such that when the feed is at the limit of its back and down movement, and accordingly the cleaning blades carried by the feed at the limit of their down movement, the top comb, then at the limit of its highest raised position, will lie within the housing formed by the cleaning blades in a position relatively close to and almost parallel with the blades 5 of the cleaner with the teeth of the comb raised well above the biting edges of the blades, all substantially as shown in Fig. 3. The feed and cleaning blades borne by it will now begin to raise and the top comb to come down, this relative up and down movement of the respective parts taking place before any appreciable movement in a transverse direction. In consequence the teeth of the comb and adjacent portion of the comb to which the teeth are soldered will pass through the apex 75

formed by the blades, the parts then assuming a position substantially as shown in Fig. 4. The teeth will pass through the blades easily, there being no undue tensioning of the blades if any, 5 their inclination to the opposite sides of the teeth, respectively, permitting of an easy passage of the teeth between and beyond their biting edges. The feed will now begin to move forward carrying with it the cleaning blades. The top comb will 10 also move forward, there then occurring some slight change in the relative positions of the top comb and cleaner blades (see Fig. 5). The teeth of the comb however are still protruding. As the feed reaches the limit of its forward movement 15 and the top comb has moved forward to the limit of its forward movement, the feed and cleaner blades borne by it will begin to lower and go back while the top comb begins to raise. It is at this time, owing to the drawing apart or separation 20 of the cleaner blades and the top comb, that the cleaning operation takes place, the relative position of the cleaner blades and top comb then being substantially as shown in Fig. 6. There it will be seen that the top comb has attained a 25 changed position with relation to the cleaner blades from its initial position first referred to, and the comb has moved away from the blades 5 and lies near to and approximately parallel with the blades 6 of the cleaner. This change in the 30 relative position of the comb with relation to the blades of the cleaner has the effect, with the teeth of the comb then protruding beyond the biting edges of the blades, of tensioning the blades, the comb fulcruming on the biting edge 35 7 of the cleaner blades 5 and acting as a lever to displace the blades 6 with relation to the blades 5 and thereby flex and tension the blades 6. In fact both sets of blades are then tensioned, the effect however being more appreciable with relation to the blades 6. It is at this time that the 40 comb and cleaning blades draw apart, the feed carrying the blades moving down to go back to its initial down position, and the comb moving up to go back to its initial position first referred 45 to.

As the cleaning blades and comb draw apart for effecting the cleaning operation all the blades, and especially the blades 6, will be more or less tensioned. The blades 5 highly resistant to displacement, will engage the teeth of the comb at 50 an angle best adapted for stripping material from the teeth without rasping the teeth. At the same time the blades 6 working on the other side of the teeth and tensioned as aforesaid, will engage the teeth at an angle substantially like the angle of the blades 5 or with an angularity best adapted 55 for cleaning the teeth but without a rasping effect. The major cleaning operation will come upon the blades 6 and the biting edge or edges of these blades will be almost fixedly maintained 60 as the teeth of the comb draw by them, owing to the then tensioned condition of the blades and the fact that those portions of the blades lying adjacent to their biting edges are substantially inflexible owing to the bends 17 in the blades. On 65 account of these bends the tensioning of the blades 6 will be occasioned by bending or flexing those portions of the blades lying between the bends 17 and the bound edges of the blades. 70 These portions are highly resistant to bending and if bent exert a high degree of tension. Consequently the biting edges of the blades 6 will be maintained to most effectually clean the teeth of the comb as the teeth draw inwardly by them, 75 and this without rasping the teeth. Any further

bending of the blades 6 must come upon these same localized parts of the blades with the effect that displacement of the blades by matter upon the teeth is practically impossible and the teeth are effectively cleaned. 5

I claim:

1. A cleaner for the top comb of combing machines comprising sets of blades angularly arranged and presenting biting edges adapted to engage the opposite sides of the teeth of the comb, 10 a frame to which the inner edge portions of said respective sets of blades are secured, sectional plates fixed to said frame and backing one of said sets of blades for stiffening them whereby said blades will be resistant to application of force at 15 the biting edges thereof tending to flex them, the other of said sets of blades being angularly bent whereby they are made highly resistant to flexure on application of force at the biting edges thereof tending to flex them. 20

2. In a combing machine the combination comprising a top comb, a feed, a cleaner for the top comb comprising blades angularly arranged and presenting biting edges adapted to engage the opposite sides of the teeth of the comb during the 25 operation of the machine, a frame to which the inner edge portions of the respective blades are secured, one of said blades being angularly bent whereby flexure thereof will be substantially confined to the portion of the blade lying between 30 the bend therein and the portion thereof fixed to said frame on displacement of the biting edge thereof away from the other of said blades, said other blade being substantially inflexible and of longer projection than the bent blade, means for 35 securing said frame to the feed to be movable therewith, and mechanism for operating said top comb and feed respectively whereby the teeth of the comb will pass from out of the housing formed by said blades between the biting edges 40 thereof when the comb lies substantially adjacent said longer blade, thence the comb move with relation to said blades into a position substantially adjacent said bent blade whereby the teeth will fulcrum on the biting edge of the longer 45 blade and thereby the teeth will operate to flex the bent blade in the portion thereof lying between the bend therein and the portion thereof fixed to said frame, and the comb afterwards withdraw into said housing from between the 50 biting edges of the respective blades when said bent blade is flexed as aforesaid. 55

3. A cleaner for the top comb of combing machines comprising blades angularly arranged and presenting biting edges adapted to engage the 60 opposite sides of the teeth of the comb in the operation of the machine, a frame to which the inner edge portions of said blades are secured, one of said blades being angularly bent whereby flexure thereof will be substantially confined to 65 the portion of the blade lying between the bend therein and the portion thereof fixed to said frame on displacement of the biting edge thereof away from the other of said blades, said other blade being substantially inflexible and of longer 70 projection than the bent blade, whereby the teeth of the comb when protruding through the biting edges of the respective blades will in the operation of the machine fulcrum on the biting edge of the longer projecting blade and thereupon operate as a lever to flex the bent blade. 75

4. A cleaner for the top comb of combing machines comprising sets of blades angularly arranged and presenting biting edges adapted to engage the opposite sides of the teeth of the comb 75

in the operation of the machine, a frame to which the inner edge portions of said respective sets of blades are secured, the blades of one of said sets of blades being angularly bent whereby 5 flexure thereof will be substantially confined to the portions of the blades lying between the bends therein and the portions thereof fixed to said frame on displacement of the biting edges thereof away from said other set of blades, the 10 blades of said other set of blades being substantially inflexible and longer than the blades of the bent set of blades whereby the teeth of the comb when protruding through the biting edges of the respective sets of blades will in the operation 15 of the machine fulcrum on the biting edges of the longer projecting set of blades and thereupon operate as a lever to flex the bent set of blades.

5. In a combing machine the combination comprising a top comb, a feed, a cleaner for the top comb including sets of blades angularly arranged and presenting biting edges adapted to engage the opposite sides of the teeth of the comb during the operation of the machine, a frame to 20 which the inner edge portions of the respective sets of blades are secured, one set of blades being angularly bent whereby flexure thereof will be 25

substantially confined to the portion thereof lying between the bend therein and the portion thereof fixed to said frame on displacement of the biting edge thereof away from said other set of blades, said other set of blades being substantially inflexible and longer than the bent set of blades, means for securing said frame to said feed to be movable therewith, and mechanism for operating the said top comb and feed, respectively, whereby in the operation of the machine the 10 teeth of the comb will, when the comb is lying substantially adjacent the longer projecting set of blades, pass from out of the housing formed by said sets of blades between the biting edges thereof to occupy an engaging position, thence 15 the comb fulcruming on the biting edge of the longer set of blades will turn with relation to said sets of blades into a position substantially adjacent the bent set of blades and thereby the comb will operate to flex the bent set of blades, 20 and the comb, then occupying a position substantially adjacent the bent set of blades and when said bent set of blades are flexed as aforesaid, will withdraw between the biting edges of the respective sets of blades back into said 25 housing.

NORMAN HOWARD.
